[57] ABSTRACT

In order to provide merchant lengths from a rolled length of stock, the stock is initially divided into lengths which are a multiple of a merchant length, the multiple lengths are cooled and batched, and the batches are then divided into merchant lengths. As the total rolled length will not be an integral multiple of a merchant length, there will usually be a discard length. In order to make it easy to remove the discard length mechanically, the method is carried out so that the rolled length of stock is divided into a number of integral multiple lengths of a merchant length together with a last multiple length which is an integral multiple of a merchant length plus a discard length and is longer by the discard length than the longest integral multiple length in the respective batch.

DIVIDING ROLLED LENGTHS OF STOCK INTO MERCHANT LENGTHS

BACKGROUND OF THE INVENTION

The invention relates to a method of dividing rolled lengths of stock (which may be of any suitable section) into merchant lengths. The rolled lengths of stock are initially divided into integral multiple lengths of the merchant lengths (such multiple lengths may be termed part-lengths) prior to being cooled in a cooling bed, with due reference to the maximum and minimum lengths permitted by the cooling bed and with reference to the total length of each length of stock as measured and computed, a plurality of multiple lengths are batched together, and each batch is divided into merchant lengths.

In the method described in "Kleipzig Fachberichte" 80 (1972), pages 104/108, prior to dividing the rolled lengths into order lengths or merchant lengths, they are subdivided upstream of the cooling bed into such multiple lengths as give optimum utilization of the cooling bed; thus discard lengths are obtained when the multiple lengths are subdivided by cold shears or saw at a position downstream of the cooling bed.

However, it is impossible to avoid an unsaleable discard length being yielded from the last multiple length when the whole rolled length is subdivided. The discard lengths must then be awkwardly separated by manual means from the merchant lengths of, if they remain in a bundle of merchant lengths, the price per weight of the bundle must be correspondingly reduced. Manual sorting not only requires an operator but also takes additional time so that output is reduced. In some plants, in order to avoid this, the last multiple length is cut off together with the short discard length, upstream of the cooling bed, and is supplied for further processing to a discard trimming device. However, this procedure is also awkward and moreover calls for additional apparatus.

Attempts have also been made to permit discard-free cutting by the saw through precise predetermination of the charge length or charge weight of the billets. These attempts failed because of the difficulties encountered when attempting to eliminate effects, during rolling, of temperature differences, groove wear, scale and the like on the length of the finished rolled length of stock.

DESCRIPTION OF THE INVENTION

According to the invention, at least the last multiple length from the whole rolled length of stock is made longer by a discard length than the longest integral multiple length within a batch for cold shearing; if desired, the discard length of a whole rolled length of stock may be distributed over two multiple lengths.

The method presupposes that the length of the cooling bed is longer by approximately one merchant length than the maximum permissible integral multiple length so that the calculated discard length can be added to the longest integral multiple length.

The method of the invention ensures that when the multiple lengths, which are delivered together in batches, are subsequently divided into merchant lengths, the discard lengths are cropped off last and can be easily ejected transversely to the delivery table.

The charge weight of the billet must form the basis for calculating the discard length. This weight can be

supplied to a computer which calculates the total rolled length by reference to the initial and final cross-sections and controls shears which are disposed upstream of the cooling bed in such a way that the rolled length of stock, whose length is precalculated, is subdivided into integers of multiple lengths of the merchant lengths; the multiple lengths from one total rolled length can be of different magnitude with respect to each other as well with respect to those of a different total rolled length. Due allowance must be made for the fact that the multiple lengths may vary only within the maximum and minimum lengths which are to be delivered to the cooling bed, the longest integral multiple length having to be smaller than the length of the cooling bed by the amount of one merchant length.

Since the discard length or the total rolled length can only be theoretically precalculated, it is necessary to take into account any changes of length which might occur in practice. These changes may be the result of errors in defining the charge weight of the billet or they may be due to variations in the amount of scale and cropping end lengths or they may be due to cross-sectional changes which in turn are the result of groove wear and temperature differences in the rolled stock.

The length changes which result from these variables may amount to up to 15 m under unfavorable conditions, given a billet charge weight of 1,000 kg and a finished diameter for the rolled stock of 12 mm. In order to detect these differences by check measurements, to enable them to be taken into account during the subdividing operation, the last but one or the last but one and the last but two multiple lengths may be made shorter by one or more merchant lengths than the maximum integral multiple length within one batch, and the end of each rolled length of stock may be sensed prior to cutting off said last but one or said last but one and last but two multiple lengths, said sensing being used to calculate the deviation of the actual rolled length from the calculated rolled length, such deviation being used to re-calculate the lengths of said last but one or said last but one and last but two multiple lengths when they are cut off.

BRIEF DESCRIPTION OF THE DRAWINGS

The invention will be further described, by way of example, with reference to the accompanying drawings, in which:

FIG. 1 is a diagrammatic view showing the path of a bar from a last rollstand to cold shears;

FIG. 2 shows a batch of multiple lengths prior to being subdivided into merchant lengths; and

FIG. 3 shows four shear batches formed from five billets.

DESCRIPTION OF PREFERRED EMBODIMENT

A bar 2 is discharged from a last rollstand 1, and is subdivided by flying shears 3 into multiple lengths which are then supplied to a run-up roller table 4 on which they are decelerated in a conventional manner. The multiple lengths are then passed through a cooling bed 5 and at the end thereof are collected on a delivery roller table 6 in batches corresponding to the usable width of the roller table 6; the batches are supplied to cold shears or a cold saw 7 for subdividing into merchant lengths.

A measuring position 8, incorporating a photocell in a conventional manner, is disposed upstream of the fly-

ing shears 3 and signals the passage of the leading bar end to a computer 9. The bar velocity is transferred to the computer 9 in a conventional manner, for example by means of a tachometer 12 which is mounted on the last rollstand 1 and takes into account the roll diameter and the final cross-section of the bar. The computer 9 has already precalculated the optimum multiple lengths and the prospective discard lengths before the rolled bar has been fed in, namely from the charge weight and by taking into account the preceding and following rolled bars, the specified merchant length and the minimum and maximum permissible lengths in the cooling bed. The computer 9 controls the shears 3 via a pulse transmitter 11 in such a way that the total rolled length is subdivided into the calculated multiple lengths. The discard length is included in the last multiple length, which is also the longest length.

In order to allow for deviations from the calculated total rolled length when the rolled bar is subdivided, the multiple lengths are appropriately pre-calculated on the basis that the multiple length preceding the last multiple length or the two multiple lengths preceding the last multiple length will be cut shorter by one or more merchant lengths than the maximum multiple length; in this manner the said two multiple lengths may actually be cut even shorter than the pre-calculated length or longer than the pre-calculated length by one or more merchant lengths. To this end it is necessary that the rolled bar length, calculated on the basis of the billet charge weight, is once again sensed prior to the last multiple length cuts. This may be done by detectors 10 which are disposed at a sufficient distance from the shears in the rolling train and which determine by check measurements any deviations from the pre-calculated rolled bar length and transmit the value to the computer 9. The computer 9 is then able to subsequently distribute the length deviations from the pre-calculated rolled bar length as determined by the check measurement over the two shortened multiple lengths which precede the last length. Depending on the magnitude of the deviation, one or more merchant lengths will be subtracted from the multiple lengths for a negative deviation and will be added thereto for a positive deviation.

FIG. 1 shows by reference to three examples the manner in which length deviations from the calculated rolled bar length, caused by different rolling conditions, are distributed over the individual multiple lengths.

The pre-calculation for bar No. 1 initially indicated that the first multiple length must be cut shorter than the maximum multiple length by one merchant length while the subsequent multiple lengths with the exception of the two multiple lengths preceding the last length may have the maximum length. Check measurements then found that the rolled bar was longer by two merchant lengths than it should be on the basis of the charge weight and final cross-section. Accordingly, the two multiple lengths preceding the last multiple length were also cut to the maximum length.

In the case of bar No. 2, check measurement yields a negative deviation from the calculated length by approximately one merchant length. The multiple length preceding the last length therefore had to be cut shorter than the maximum permissible length X_{max} · VL by two merchant lengths VL so that the last multiple length X_{max} · VL + discard length RL together be-

come longer than the maximum multiple length X_{max} · VL permitted by the cooling bed (this is possible because the discard length can overhang in the cooling bed and the maximum length permitted by the cooling bed is greater than the maximum integral multiple length permitted by the cooling bed).

FIG. 2 shows how the multiple lengths of the bar No. 2 are disposed upstream of the shears 7 and the discard length RL remains on the last length of the total rolled bar length after cutting off all the merchant lengths. The discard length in this case can be easily pulled to one side either manually or by an automatically actuated pusher.

FIG. 3 shows the manner in which the computer 9 operates in conjunction with cold shearing batches which have different maximum multiple lengths. The input constants may for example be defined as follows:

a)	Merchant length	1 VL = 10 m
b)	Minimum permissible length in the cooling bed	70 m = 7 VL
c)	Maximum permissible integral multiple length in the cooling bed	100 m = 10 VL
d)	Maximum possible deviation of the rolled bar length from the calculated length	10 m = 1 VL
e)	5 multiple lengths form one cold shearing batch	

The computer 9 defined the following probable lengths from the weights of the billet:

Bar 1 = 367 m	yields	36 VL + RL
Bar 2 = 314 m	yields	31 VL + RL
Bar 3 = 362 m	yields	36 VL + RL
Bar 4 = 335 m	yields	33 VL + RL
Bar 5 = 318 m	yields	31 VL + RL

The last but one multiple length of a bar must be shorter by at least one merchant length than the maximum multiple length and must be longer by at least one merchant length than the minimum permissible length in the cooling bed so that maximum possible deviations can be subtracted or added after the check measurement.

The computer divides as follows:

Bar 1:	1st multiple length = 9 VL	)
	2nd multiple length = 8 VL	) All in first cold shear
	3rd multiple length = 9 VL	) batch
	4th multiple length = 10 VL + RL	)
	Total 36 VL + RL	)

It is found for bar 2 that the maximum multiple length in this case can be only 9 VL since the minimum multiple length must be at least 7 VL and the last but one multiple length must be at least 8 VL. Bar 2 is therefore divided as follows:

Bar 2:	1st multiple length = 7 VL	) First cold shear batch
	2nd multiple length = 7 VL	)
	3rd multiple length = 8 VL	) Second cold shear batch
	4th multiple length = 9 VL + RL	)
	Total 31 VL + RL	)

The first two multiple lengths of the bar 3 are required for the second cold shear batch. They must therefore not be longer than 9 VL. Thereafter the computer 9 must set the maximum multiple length again to 10 VL because in the event of an excess quantity and given a maximum multiple length of 9 VL, the computer could not add anything to the last but one multiple length, which would already be 9 VL.

Bar 3:	1st multiple length	= 9 VL	)	Second cold
	2nd multiple length	= 8 VL	)	shear batch
	3rd multiple length	= 9 VL	)	
	4th multiple length	= 10 VL + RL	)	Third cold shear batch
	Total	36 VL + RL		

The division of bar 4 will be initially calculated as follows:

Bar 4:	1st multiple length	= 7 VL	)	
	2nd multiple length	= 7 VL	)	Third cold
	3rd multiple length	= 9 VL	)	shear batch
	4th multiple length	= 10 VL + RL	)	Fourth cold shear batch
	Total	33 VL + RL		

On reaching bar 5, the computer discovers that again only one maximum multiple length of 9 VL can be formed. However, the division of bar 4 must be re-calculated because the last multiple length of bar 4, which together with the multiple lengths of bar 5, forms the fourth cold shear batch, had already been set to 10 VL + RL. Bar 4 is therefore divided as follows:

Bar 4:	1st multiple length	= 7 VL	)	
	2nd multiple length	= 9 VL	)	Third cold
	3rd multiple length	= 8 VL	)	shear batch
	4th multiple length	= 9 VL + RL	)	Fourth cold shear batch
	Total	33 VL + RL		

Bar 5 is divided as follows:

Bar 5:	1st multiple length	= 7 VL	)	
	2nd multiple length	= 7 VL	)	All in
	3rd multiple length	= 8 VL	)	fourth cold
	4th multiple length	= 9 VL + RL	)	shear batch
	Total	31 VL + RL		

In this way the division of the entire charge is pre-calculated by the computer immediately after the billet weight is measured upstream of the furnace. The manner in which a bar is to be divided is therefore defined long before it is rolled. The computer therefore has sufficient time to re-calculate the division of a bar, if necessary, as shown by the example of bar 4.

Bars which are rejected and removed due to defects are treated as though they had not been removed if there is only a short hold up; that is to say the respective cold shear batch is only incompletely filled and

travels in this way through the cold shears. If the hold up is more prolonged, the computer will re-calculate the division of the subsequent bars.

For very long merchant lengths (for example 24 m), it is advantageous to distribute the discard length over the last two multiple lengths in order to minimize the cooling bed overhang which is required for the discard lengths.

We claim:

10. 1. A method of dividing rolled lengths of stock into merchant lengths, comprising:

dividing each said rolled length of stock into a number of multiple lengths;
cooling said multiple lengths in a cooling bed;
collecting into batches said multiple lengths from a number of said rolled lengths of stock; and
dividing said batches into said merchant lengths and at least one discard length;
at least the last one of said multiple lengths being

equal to an integral multiple of said merchant length plus a discard length and the remainder of said multiple lengths being equal to an integral multiple of said merchant length, said multiple length which includes said discard length being longer by said discard length than the longest integral multiple length in the respective said batch,

45 and all said multiple lengths being respectively not greater than or less than the maximum or minimum length permitted by said cooling bed.

2. A method as claimed in claim 1, wherein the last but one or the last but one and last but two said multiple lengths are made shorter by at least one said merchant length than said longest integral multiple length in the respective batch, and wherein the end of each said rolled length of stock is sensed prior to cutting off said last but one or said last but one and last but two multiple lengths, said sensing being used to calculate the deviation of the actual rolled length from the calculated rolled length, such deviation being used to re-calculate the lengths of said last but one or said last but one and last but two multiple lengths when they are cut off.

55 3. A method as claimed in claim 1, wherein the discard length of a whole said rolled length of stock is distributed over two said multiple lengths.

4. A method as claimed in claim 2, wherein the discard length of a whole said rolled length of stock is distributed over two said multiple lengths.
